2 SHEETS—SHEET 2.

UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

CYLINDER-DRIVING MECHANISM FOR PRINTING-PRESSES.

1,359,862.

Specification of Letters Patent. Patented Nov. 23, 1920.

Application filed March 6, 1920. Serial No. 363,849.

To all whom it may concern:

Be it known that I, HENRY F. BECHMAN, a citizen of the United States, residing at Battle Creek, in the county of Calhoun and State of Michigan, have invented certain new and useful Improvements in Cylinder-Driving Mechanism for Printing-PresSES; and I hereby declare that the following is a full, clear, and exact description thereof, reference being had to the accompanying drawings, which form part of this specification.

The present invention is an improvement in rotary web printing presses of the single-page tubular-plate type disclosed in my Patents Nos. 867,230, of October 1, 1907, and 1,240,008, of September 11, 1917. In particular the present invention is an improvement upon the plate driving gearing shown in Patent No. 1,233,025 of April 17, 1917.

The object of the present invention is to provide novel gearing between the plate and impression cylinders which will permit the tubular plates to be slipped on or removed from either or both ends of the plate cylinder without having to remove any gears.

I will explain the invention with reference to the accompanying drawings which illustrate one practical embodiment thereof, and then summarize in the claims the novel features of construction and novel combinations of parts for which protection is desired.

In said drawings Figure 1 is a transverse section through part of a printing press, showing in side elevation a plate cylinder adapted to carry tubular plates and a coacting impression cylinder; and the novel gearing whereby the cylinders are driven and maintained in constant proper geared peripheral relation.

Fig. 2 is a top plan view of Fig. 1.

Fig. 3 is an enlarged elevation of the gearing between the cylinders at the left hand end of Figs. 1 and 2.

Fig. 4 is a similar elevation of the gearing between the cylinders at the right hand end of Figs. 1 and 2.

Fig. 5 is a diagrammatical view illustrating the relation between the gapped-gears at opposite ends of the impression cylinder for driving the plate cylinder.

The drawings illustrate only one printing couple, comprising a plate cylinder 1, and a coacting impression cylinder 2, which in the example shown is twice the diameter of the plate cylinder.

The trunnions of the shafts of the cylinder 2 are journaled in bearings of any suitable construction, mounted in boxes 2^b on the side frames F. The cylinder 2 is preferably laterally adjustable toward and from the plate cylinder and the bearings in the boxes 2^b may be adjustable in the well known manner to regulate the impression pressure or contact between the cylinder 2 and the plate cylinder 1.

The plate cylinder 1 is adapted to carry single-page-tubular-plates, such as shown in my patents above referred to, and is of small diameter so that such tubular plates can be slipped endwise on or off the cylinder and over the bearings which support the cylinder at the ends thereof. In the example shown the plate cylinder is adapted to carry four or more tubular plates and therefore the journal bearings for such plate cylinder, at each end both ends thereof, are such that the plates can be slipped endwise over such bearing on or off the cylinder.

The plate cylinder 1 is journaled in bearings 1^b, which, in the example shown, are applied to the side of the bearings 2^b. These bearings (see Fig. 3) are shaped substantially as shown in my Patent No. 979,919, December 27, 1910, so that the tubular plates P can be slipped endwise over these bearings onto or off of the plate cylinder.

The plate cylinder must have a constant geared relation with the impression cylinder, and therefore in order to enable the plates to be placed on or removed from the plate cylinder at either end I employed gapped gears to drive the plate cylinder as disclosed in my Patent No. 1,233,025, and also provided means whereby when the gapped gear at one end of the plate cylinder was out of mesh, the gapped gear at the other end of the plate cylinder was in mesh thus keeping the two cylinders in constant geared relation, as described in my said patent.

My present invention provides novel gap-gearing between the plate cylinder and the impression cylinder whereby the plate and

impression cylinders are kept in constant true geared relation; such novel gearing being as follows.

As shown in the drawings the impression cylinder 2 carries a gear 2^d which meshes with a gear 4^a on a countershaft 4^a suitably journaled in the side frames of the machine preferably below the impression cylinder.

On each end of the shaft 1^a of the plate cylinder 1 is keyed a pinion 1^c, which meshes with an annular gear 3^c, journaled on a large stud 3 which may be formed on or rigidly attached to the outer side of the adjacent box 2^b of cylinder 2, in any suitable manner. As shown the stud 3 is fastened to the box 2^b by bolts 3^b.

Each stud 3 is eccentric to the shaft 2^a of the cylinder 2 and one of the studs 3 at the drive end of the impression cylinder is provided with a slot or opening 3^a for the passage of the cylinder shaft; said slot being sufficiently large or long to permit of the desired lateral adjustment of the cylinder 2 relative to the cylinder 1.

Each gear 3^c meshes with a gear 4^c on the adjacent end of the shaft 4. The gears 3^c are of the same diameter as the gears 2^d; the gears 4^c are of the same diameter as the gears 4^a; and the gears 1^c are one-half the diameter of the gears 3^c. With this arrangement and proportion of gears the plate cylinder will be caused to make two revolutions for each revolution of the impression cylinder; the latter being twice the diameter of the plate cylinder; thus the plate and impression cylinders have the same peripheral speeds.

The axis of the shaft 4^a is equidistant from the axis of the impression cylinder shaft 2^a and the axes of the impression cylinder driving gears 3^c; so that the gears 2^d and 3^c are driven in exact time and synchronism; and as the gears 1^c, 3^c, and 4^c, at each end are duplicates, they have the same relative proportional speeds.

Each gear 3^c, however, is provided with a peripheral gap 3^g, which during each revolution of such gear 3^c comes opposite its related gear 1^c; as indicated in Figs. 4 and 5; the gap then forming space between the gears through which space a tubular plate P can be slipped endwise on or off the cylinder over the reduced shank of the plate cylinder bearing. The respective gears 3^c at opposite ends of the cylinder 1 are so set that the gaps 3^g therein are preferably 180° apart, as indicated in Fig. 5, and consequently at no time can both gears 3^c be simultaneously out of mesh with both gears 1^c; but whenever and while one gear 3^c is out of mesh with its related gear 1^c (i. e. while the gap in such gear 3^c is opposite or passing such gear 1^c) the other gear 3^c is in mesh with its related gear 1^c. Consequently at any and all times there is a constant posi-

tive driving gear connection maintained between the impression cylinder 2 and the plate cylinder 1.

When the pressman desires to place plates on the plate cylinder, or to remove plates therefrom (at, for instance, the left hand side of the press) he turns the cylinders until the gap 3^g in the left side gear 3^c comes opposite the related gear 1^c on the plate cylinder 1 (see Figs. 4 and 5), and while such gap is in the position indicated in Figs. 4 and 5, he can slip the plates on or off the cylinder over the bearing at that side of the machine, the plates passing over the gear 1^c and between it and the related gear 3^c through the gap in such gear 3^c. At such time the plates could neither be removed from nor applied to the end of the plate cylinder at the right hand side of the press.

If the operator desires to put plates on the plate cylinder or remove them therefrom at the right hand side of the press he causes the mechanism to rotate the plate cylinder one revolution, which will first bring the gap in the gear 3^c at the left hand side of the machine again into mesh with its related gear 1^c, and thereafter bring the gap in the gear 3^c at the right hand side of the press opposite its related gear 1^c; then plates can be placed on or taken off the plate cylinder at the right hand side of the press.

While I have shown in the drawings the plate cylinders as constructed to carry four plates each, any less number of plates may be placed thereon according to the size of the paper it is desired to print; and, if desired, the plate cylinders may be made long enough to carry five or more plates.

In this form of gearing there is always a fixed driving relation between the plate and impression cylinders which remains constant regardless of the adjustment of the impression cylinder toward or from the plate cylinder, because the gear 3^c is not shifted with the impression cylinder to or from the plate cylinder but remains constantly at a fixed distance from the axis of the plate cylinder; and the gear 2^d mounted on the impression cylinder has a rolling movement relative to the gear 4^a, but is not separated therefrom during the adjustment of the impression cylinder.

A further advantage of the present construction over that shown in my aforesaid patent is that there is always a sufficient, reliable and positive geared relation between the plate and impression cylinders which results from the fact that the gears 3^c are about twice the diameter of the gears 1^c, instead of being of like size.

Further by having the gears 3^c fixed relatively to the gears 1^c, and not shifted by the impression adjustment of cylinder 2, there is no variation of pitch line mesh between the gears 3^c and 1^c, and consequently no

chatter or jar when the gaps in gears 3° are passing the gears 1°, thus obviating any possibility of clashing between the gears 1° and 3° at any time in the operation of the 5 press.

What I claim is:

1. In a printing press the combination of an impression cylinder; a plate cylinder; a gear on the plate cylinder; a gear meshing 10 with the plate-cylinder gear and mounted beside the end of the impression cylinder on an axis eccentric to the axis of the impression cylinder; and gearing between the impression cylinder and said eccentrically mounted gear, whereby the plate cylinder is rotated at the same peripheral speed as the impression cylinder.

2. In a printing press the combination of an impression cylinder; a plate cylinder beside the impression cylinder adapted to carry single page tubular plates; a gear on the plate cylinder shaft; a peripherally gapped gear meshing with the plate cylinder gear and mounted beside the end of the impression cylinder on an axis eccentric to the axis 25 of the impression cylinder; and gearing between the impression cylinder and said eccentrically mounted gear whereby the plate cylinder is rotated at the same peripheral speed as the impression cylinder.

3. In a printing press, the combination of a plate cylinder adapted to carry tubular plates, a journal bearing for the plate cylinder whereby such plates may be slipped endwise on or off the cylinder; a gear on the end of the plate cylinder; a gapped gear meshing with the plate cylinder gear, said gapped gear being journaled beside the end of the impression cylinder but on an axis eccentric thereto; and gearing between the impression cylinder and said eccentrically mounted gear, whereby the plate cylinder is rotated at the same peripheral speed as the impression cylinder.

4. In a printing press the combination of an impression cylinder; a plate cylinder coacting with the impression cylinder adapted to carry single page tubular plates; a journal bearing for such cylinder whereby such plates can be slipped endwise on or off the plate cylinder over such bearing; an eccentrically mounted gear meshing with the plate cylinder gear, a journal for said eccentrically mounted gear adjacent the end of the impression cylinder, said journal surrounding the impression cylinder shaft; and gearing between the impression cylinder and the eccentrically mounted gear.

5. In a printing press the combination of an impression cylinder; a plate cylinder coacting with the impression cylinder adapted to carry single page tubular plates; a journal bearing for such cylinder whereby such plates can be slipped endwise on or off the plate cylinder over such bearing; a gapped

gear meshing with the plate cylinder gear; a journal for said gapped gear mounted eccentric to the axis of the impression cylinder and adjacent the end thereof; said journal surrounding the impression cylinder shaft; and gearing between the impression cylinder and the gapped gear; substantially as described.

6. In a printing press, the combination of a plate cylinder adapted to carry tubular plates; a journal bearing for each end of the cylinder whereby such plates may be slipped on or off either end of the cylinder; a gear on each end of the plate cylinder; an impression cylinder coacting with the plate cylinder; a gapped gear meshing with each of the plate cylinder gears, said gapped gears being journaled beside the ends of the impression cylinder but eccentric thereto; the gaps in the two eccentrically mounted gears being so disposed that when either gapped gear is disengaged from its related plate cylinder gear, the other gapped gear is in engagement with its related plate cylinder gear.

7. In a printing press, the combination of an impression cylinder; a plate cylinder coacting therewith adapted to carry tubular plates; a journal bearing for each end of the plate cylinder whereby such plates may be slipped on or off either end of such cylinder; a gear mounted upon each end of the plate cylinder; gapped gears meshing with related gears on each end of the plate cylinder; said gapped gears being mounted eccentrically of the axis of the impression cylinder and surrounding the impression cylinder shaft; and gearing between the impression cylinder and the gapped gear whereby the plate and impression cylinders are rotated at the same peripheral speed.

8. In a printing press, the combination of an impression cylinder; a plate cylinder coacting therewith adapted to carry tubular plates; a journal bearing for each end of the plate cylinder whereby such plates may be slipped endwise on or off either end of the cylinder; a gear smaller than the journal bearing mounted upon each end of the plate cylinder; a gapped gear meshing with each gear on each end of the plate cylinder, said gapped gears being mounted upon studs disposed eccentrically of the axis of the impression cylinder and surrounding the impression cylinder shaft; and gearing between the impression cylinder and the said gapped gears whereby the plate and impression cylinders are rotated at the same peripheral speed.

9. In a printing press, the combination of a plate cylinder adapted to carry tubular plates; a journal bearing for each end of said cylinder whereby such plates may be slipped on or off either end of such cylinder; an impression cylinder beside and co-

acting with the plate cylinder; a gapped gear journaled beside each end of the impression cylinder and eccentric to and surrounding the axis thereof; gearing between 5 said gapped gears and the said impression cylinder; and pinions on each end of the plate cylinder respectively meshing with the opposed adjacent gapped gears; the gapped gears being so disposed that when 10 either gapped gear is disengaged from its related plate cylinder gear, the other gapped gear is in engagement with its related plate cylinder gear.

10. In a printing press; the combination 15 of an impression cylinder; a plate cylinder coacting with the impression cylinder adapted to carry single page tubular plates; journal bearings for the plate cylinder whereby such plates can be slipped end- 20 wise on or off the plate cylinder over such bearings; a gapped gear meshing with each plate cylinder gear; journals for said gapped gears mounted eccentric to the axis 25 of the impression cylinder and adjacent the ends thereof said journals surrounding the impression cylinder shaft; a counter-shaft; gearing between the counter-shaft and the impression cylinder shaft; and gearing between the counter-shaft and the gapped 30 gears.

11. In a printing press, the combination 35 of a plate cylinder adapted to carry tubular plates; journal bearings for each end of the cylinder whereby such plates may be slipped endwise on or off either end of the plate cylinder; an impression cylinder beside and coacting with the plate cylinder; a counter-shaft beside the impression cylinder; gearing between the impression cylinder and said counter-shaft; gapped gears 40 journaled beside each end of the impression cylinder and eccentric to and surrounding the axis thereof; gearing between said gapped gears and the said counter-shaft;

and pinions on each end of the plate cylinder 45 respectively meshing with the opposed adjacent gapped gears; the gapped gears being so disposed that when either gapped gear is disengaged from its related plate cylinder gear the other gapped gear is in 50 engagement with its related plate cylinder gear, substantially as described.

12. In a printing press the combination of 55 an impression cylinder; a plate cylinder beside the impression cylinder adapted to carry single page tubular plates; gears on the plate cylinder shaft; peripherally gapped gears meshing with the plate cylinder 60 gears and mounted beside the ends of the impression cylinder on an axis eccentric to the axis of the impression cylinder; and gearing for driving said eccentrically mounted gears to rotate the plate cylinder at the same peripheral speed as the impression cylinder. 65

13. In a printing press, the combination 70 of a plate cylinder adapted to carry tubular plates; a journal bearing for each end of the cylinder whereby such plates may be slipped on or off either end of the cylinder; a gear on each end of the plate cylinder; an impression cylinder coacting with the plate cylinder; a gapped gear meshing with each of the plate cylinder gears, said gapped 75 gears being journaled beside the ends of the impression cylinder but eccentric thereto; the gaps in the two eccentrically mounted gears being so disposed that when either gapped gear is disengaged from its related plate cylinder gear, the other gapped gear 80 is in engagement with its related plate cylinder gear; and gearing for driving the gapped gears so as to rotate the plate cylinder at the same peripheral speed as the impression cylinder. 85

In testimony that I claim the foregoing as my own, I affix my signature.

HENRY F. BECHMAN.
